United States Patent Office

Des. 193,072
Patented June 19, 1962

193,072

WASTE RECEPTACLE

Phyllis G. Betnar, 6200 Brookville Road,
Indianapolis, Ind.

Filed Aug. 7, 1961, Ser. No. 66,226

Term of patent 14 years

(Cl. D58—17)

The FIGURE on the drawing is a perspective view of a waste receptacle showing my new design, the scroll type ornamentation continues in the same fashion around the receptacle.

I claim:

The ornamental design for a waste receptacle, as shown and described.
